(57) **CLAIM**

The ornamental design for an absorbent article with channels, as shown and described.

DESCRIPTION

FIG. 1 illustrates a perspective view of an embodiment of a channels design disposed on a material, included as part of an absorbent article, being worn, by a wearer, e.g. a child; FIG. 2 illustrates a front view of an embodiment of a channels design disposed on a material, included as part of an absorbent article, being worn, by a wearer, e.g. a child; FIG. 3 illustrates a right side view of an embodiment of a channels design disposed on a material, included as part of an absorbent article, being worn, by a wearer, e.g. a child, and the channels design is obstructed from view; FIG. 4 illustrates a back view of an embodiment of a channels design disposed on a material, included as part of an absorbent article, being worn, by a wearer, e.g. a child; FIG. 5 illustrates a left side view of an embodiment of a channels design disposed on a material, included as part of an absorbent article, being worn, by a wearer, e.g. a child, and the channels design is obstructed from view; and, FIG. 6 illustrates a bottom view of an embodiment of a channels design disposed on a material, included as part of an absorbent article, being worn, by a wearer, e.g. a child. The channels are visually distinct from the surface of the absorbent article upon which they are disposed. In various embodiments, the distinction may be exhibited as printed graphics, grooves, or combinations thereof.

The broken lines, including those showing the diaper tabs and ears, are included for the purpose of illustrating environment and forms no part of the claimed design.

1 Claim, 6 Drawing Sheets
